UNITED STATES PATENT OFFICE.

WARREN M. BRINKERHOFF, OF AUBURN, NEW YORK.

PICTURE HOOK OR HANGER.

SPECIFICATION forming part of Letters Patent No. 366,812, dated July 19, 1887.

Application filed May 10, 1887. Serial No. 237,700. (No model.)

To all whom it may concern:

Be it known that I, WARREN M. BRINKERHOFF, a citizen of the United States, residing at Auburn, in the county of Cayuga and State 5 of New York, have invented certain new and useful Improvements in Picture Hooks or Hangers; and I do hereby declare the following to be a full, clear, and exact description of the invention, such as will enable others skilled 10 in the art to which it appertains to make and use the same.

My invention relates to the class of devices known as "picture-hangers;" and it consists in certain peculiarities of construction where- 15 by the picture-supporting cord or wire is held from slipping upon its support and the accidental displacement of the picture prevented.

It is a fact well known to housekeepers that pictures in a dwelling - house are constantly 20 getting awry upon the walls or out of true perpendicular. There being nothing to prevent the cord or wire from slipping upon its support, any inconsiderate handling in dusting the room causes the cords to move upon 25 the nails or hooks, resulting in a displacement of the pictures. In case the pictures are not balanced upon their supporting hooks or nails, any sudden jar or vibration of the walls will also cause a slipping of the cord or wire on its 30 support with like results.

My improved hanger is designed to avoid this difficulty and to provide a support for a picture cord or wire which will not permit such cord to slip upon the same, and which 35 will therefore tend to keep the pictures in place upon the walls.

In the accompanying drawings I have illustrated several modes in which I have contemplated applying my invention, and such in- 40 vention is fully disclosed in the following specification and claims.

In the drawings, Figures 1, 2, 2^a, 3, and 4 are perspective views of different forms of a picture-hanger for attachment to a cornice. 45 Fig. 5 is a front view of another form of cornice-hanger. Fig. 6 is an edge view of the same. Fig. 7 is a view of a form of hanger which can be attached to the wall by a nail or screw. Fig. 8 is a like view of a hook formed 50 entirely of wire. Fig. 9 is a like view of a modified form of simpler construction.

The hanger consists of a main body, A, of any suitable material, and when designed for attachment to a cornice it is provided at its upper end with the large cornice-hook a. The 55 cord or wire supporting hook is located beneath the hook a, and below this I form one or two hooks or projections, and the cord is made to engage these in the manner shown or any equivalent way. The cord is held by this 60 means at such an angle either in respect to the cord or wire hook or to such hooks themselves that it is prevented from all slipping upon its support. In all the figures except Fig. 8 the picture-hanger is shown made 65 from a piece of plate metal, and in Figs. 1 and 3 the cord hook b is shown as made by a tongue of metal cut from the central part of the plate, and bent outward and then upward to form the hook. Below this hook the lower 70 corners of the plate are bent upward to form the hooks b' b', which I denominate the "re- 75 taining-hooks." In hanging a picture the cord or wire e is first placed upon the hook b and the picture adjusted to the proper position. The cord or wire is then grasped and placed in engagement with the retaining construction by inwardly deflecting the same, in which position it will be held against accidental displacement. 80

It will be seen that when the picture is suspended upon the cord or picture-support, and its whole weight hanging thereon, the picture can be adjusted to its desired position with little difficulty, as there is nothing to prevent 85 the cord from moving easily upon its support; but when the cord is placed within or in engagement with the retaining devices it is locked thereby and securely held in position.

In Fig. 2 the cord or wire support is formed 90 of two hooks, b² b², also integral with the plate, consisting of two pieces cut from the sides of the plate and turned upward. The retaining-hooks b³ b³ are formed of like portions of the plate turned from the sides toward the center 95 of the plate; or the retaining-hooks may be cut from the sides in a similar manner to the cord-supporting hooks and turned downward, as shown in Fig. 2^a.

In Fig. 4 the main body of the plate is bent 100 or folded transversely, so as to form a hook or support, b⁴, for the cord, and the retaining-

hooks are formed by providing the lower end of the plate with a dovetail slot and bending such lower portion of the plate outward at right angles with the main body of the hook 5 or hanger.

In the form of the device shown in Figs. 5 and 6 I dispense with the hooks for supporting the cord or wire. The plate is provided with the retaining-hooks $b'b'$, as in Figs. 1 10 and 3, and for a cord-support I provide a separate piece, C, having a pointed or wedge-shaped lower portion fitting within the retaining-hooks $b'b'$. This piece C may be made of a solid piece of metal, or it may be made of 15 plate material having its edges bent at right angles to its face to give it the necessary bearing upon the cord, and its upper side may be curved or straight, as preferred. The sides or edges are preferably grooved or hollowed to 20 receive the cord, and this grooved or hollowed portion may have transverse corrugations to give it a greater hold upon the cord. When this form of hook or hanger is employed, the cord or wire is placed around the piece C within 25 the retaining-hooks $b'b'$. The cord is adjusted without allowing the weight of the picture to come upon it until the proper position of the cord is secured, when the weight is allowed to come upon the cord, and the piece C is drawn 30 downward between the retaining-hooks, firmly clamping the cord.

In Fig. 7 I show the same form of cord and retaining-hooks as in Fig. 2. The plate A in this instance is not provided with the cornice-hook, but has near its upper end an opening to engage a nail or screw, by which it is held in position on the wall. A like form of hook is shown in Fig. 8 made from wire instead of a plate.

40 Instead of the opening in the hook or hanger to receive a screw or nail, I may attach a spur, nail, or screw to the rear side of the upper part of the plate, and secure the hook to the wall therewith; but when designed for 45 attachment to a plain surface the ordinary picture-nail or similar engagement may be used. In such cases it is not necessary that any support for the cord be provided other than the nail or similar devices. The depending 50 portion below the nail may simply consist of a body of any suitable material provided with means for engaging its support and with the herein-described constructions for confining the cord or wire below the cord-support. In 55 Fig. 9 I have shown such a form of cord-retaining hooks as in Figs. 2 and 7; but the cord-supporting hook in this case consists of the wall-engaging device, usually a nail or screw, which answers the double purpose of forming 60 a support for sustaining the weight of the picture on the wall and a support for the cord. While this form may be employed and is within the spirit of my invention, it is not my preferred form of construction.

65 It will be understood that either of the forms shown may have a cornice-hook, or it may be

attached to the wall, as hereinbefore indicated, or in any other preferred manner.

The position of the retaining-hooks may be considerably varied; but they should be so 70 located as to cause the cord or wire to be deflected considerably from its usual straight line from the cord-support to the picture-frame. I prefer to place them in a vertical line below the outer edges of the cord-support, or within 75 these positions and nearer the center of the hook, in either of which positions the cord, previous to its being secured by the retaining devices, will not ordinarily come in contact with the operative surfaces of the same. 80

It will also be observed that in the instances in which the cornice-hook is used the extended bearing of the same upon the cornice tends to prevent the vibration of the hook or hanger, and also that the locking of the cord to the 85 hook or hanger at another point, giving the cord two bearings in different horizontal planes upon the hook, has a strong tendency to prevent the lateral vibration of the picture when once secured in position. This feature 90 of my invention I regard as an important one, as it constitutes an almost sure safeguard against the accidental displacement of the picture.

I may sometimes employ but a single retaining-hook, as I have found that when placed in the positions shown in the drawings a single retaining-hook will prevent the slipping of the cord, as the bend of the cord inward beneath the cord-support will prevent its slipping in 100 one direction and the outward bend of the cord below the retaining-hook will prevent its moving in the opposite direction. 95

What I claim, and desire to secure by Letters Patent, is—

1. A picture-hanger consisting of a picture-cord support and a retaining device or devices below the cord-support for holding the cord in an inwardly-deflected position, the construction and arrangement of parts being such that the picture can be suspended upon the cord-support, and while so suspended adjusted to its proper position and the cord then be removably secured by the retaining device or devices by inwardly deflecting and engaging the 115 same therewith, as and for the purpose set forth.

2. The herein-described picture-hanger, consisting of a main body provided with means for engaging a support for the same, the said body being also provided with a cord-support and a projection or projections for holding the cord in an inwardly-deflected position below the same, whereby the picture can be suspended upon the cord-support, and while so suspended adjusted to its proper position without the 125 cords bearing against the operative surfaces of said projection or projections, and the cord can then be removably engaged with said projection or projections and held, as and for the purposes specified.

3. The herein-described picture-hanger, consisting of a plate provided with means for en-

gaging a support for the same, the said plate having a cord-support, and also provided below the cord-support with a projection or projections separate from the cord-support for holding the cord in an inwardly-deflected position, whereby the picture can be suspended upon the cord-support, and while the weight is upon the cord and its support the picture can be adjusted to the proper position and the cord then be removably secured by the projection or projections by inwardly deflecting and engaging the same therewith, for the purposes set forth.

4. The herein-described picture-hanger, consisting of a plate provided with means for engaging a support for the same, a cord-support, and two hooks below and separate from the cord-support for removably engaging both of the descending portions of the picture-cord, for the purposes specified.

5. The herein-described picture-hanger, consisting of a main body provided with means for engaging a support for the same, a support for the picture-cord, and two cord-engaging projections below the cord-support separate therefrom and within vertical lines from the outer edges of such cord-support, for the purposes set forth.

6. The herein-described picture-hanger, consisting of a plate provided with means for engaging a support for the same, a support for the picture-cord having its outer lateral edges extending nearly or quite to the edges of said plate, the said plate having below the said cord-support a centrally-depending portion of

less width than the cord-support, said depending portion being provided with two hooks for removably engaging the cord below the cord-support, for the purposes described.

7. The combination, with the support for a picture-cord, of a construction below the cord-support having two bearings for removably engaging the portions of the picture-cord below the cord-support and lying within the lines of the cord when passing directly from said support to the picture, substantially as described.

8. A picture-hanger consisting of a main body provided with means for engaging a support for the same, tending to hold it from lateral vibration upon said support, a cord-support, and a projection or projections in a different horizontal plane from the cord-support for holding the cord in an inwardly-deflected position, whereby the picture can be suspended on the cord-support, and while so suspended adjusted to its proper position without the cord bearing against the operative surfaces of said projection or projections, and the cord can then be placed in removable engagement with said projection or projections and restrained from lateral vibration and from movement upon the cord-support, substantially as described.

In testimony whereof I affix my signature in presence of two witnesses.

WARREN M. BRINKERHOFF.
